UNITED STATES PATENT OFFICE.

FRANK WOOD, OF MOUNT COMFORT, INDIANA.

AEROPLANE-MOTOR.

1,329,033.

Specification of Letters Patent. Patented Jan. 27, 1920.

Application filed December 11, 1917. Serial No. 206,646.

To all whom it may concern:

Be it known that I, FRANK Wood, a citizen of the United States, residing at Mount Comfort, in the county of Hancock and State of Indiana, have invented a new and useful Aeroplane-Motor, of which the following is a specification.

The subject of this invention is a motor of the internal combustion engine type and intended, primarily, for an aeroplane motor.

A principal object of the invention is to improve the connection between the piston rods and the main shaft.

Another object is to provide a gyroscopic element to impart rotary motion to the main shaft.

Still another object is to provide a two cycle engine.

A further object is to provide means for cooling the engine.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:

Figure 1 is a view in elevation of a motor constructed in accordance with the invention;

Fig. 2 is a front elevation, a portion of the front plate removed;

Fig. 3 is a central longitudinal section taken through a diametrically arranged pair of cylinders;

Fig. 4 is a fragmentary detail showing in end elevation the connection of the piston rod with the gyroscopic member;

Fig. 5 is a section on the line 5-5 of Fig. 4.

Referring to the drawings by numerals of reference:

In carrying out the invention there is provided a suitable cylindrical or drum-like casing 10 the central portion of the head of which is offset outwardly as at 11 and a hub 12 is provided at the center of the head of this offset portion 11. The head of the cylindrical casing 10 extends beyond the cylin-

drical body to form a flange 13, while at the other end of the body an outwardly extending annular flange 14 is formed.

Secured to the flange 14 by machine screws 15 or otherwise, is a plate 16 which forms 60 a head or closure for the casing 10. The plate 16 may be reinforced by the radially extending ribs 17 which are formed on its outer face, while a centrally disposed standard 18 projects from its inner face and this 65 standard terminates in a substantially spherical end 19, which projects into a socket 20 formed at the center of a disk or plate 21.

The plate 21 is preferably circular and may be reinforced with radial ribs 22 and 70 23 formed on its rear and front faces, respectively. An arm 24 extends forwardly from the center of the plate or disk 21 and terminates in a spherical end 25, which is journaled in a socket 26 formed in the end 75 of a crank 27. The end portion of the crank 27 is separable so as to form a divided socket to permit the spherical end 25 to be easily placed therein. This end is bound in place by the machine screws 28 or otherwise. The 80 crank 27 has a weighted extension 29 for the purpose of providing a counterbalance.

While this portion has been shown and described as a crank it is to be understood that the same may be in the form of a fly wheel if 85 desired.

The crank 27 is integral with or rigidly affixed to the drive shaft 30 which shaft is journaled in the before mentioned hub 12.

A series of cylinders 31, herein shown as 90 six, are spaced about the head of the casing 10 and are secured to the head and the flanges 13 by machine screws 32 or otherwise. The cylinders are provided with the usual spaced annular ribs 33 and with spaced 95 ribs 34 arranged on the cylinder heads for the purpose of radiating heat and cooling the cylinders. An exhaust port 35 is likewise provided in the side of each cylinder 31 and communicates with the exhaust manifold 36 which practically encircles the motor.

An inlet port 37 is provided through the flange 13 for each cylinder 31 and at these ports suitable check valves, indicated at 38, are provided. Fuel is supplied to the cylinders through the ports 37 by means of an intake manifold 39 which encircles the motor.

Each cylinder is provided with a by-pass 40 leading from the crank end to the head 110

end of the cylinder when the piston has reached the limit of its forward stroke.

Within each cylinder 31 is a piston 41 which has a short flange or deflector plate 42 projecting from its head near the periphery thereof and adapted to lie in front of and spaced slightly from the head end opening or discharge port of the by-pass 40 when the piston is in its crank end position.

10 This serves to direct the inflowing gases toward the cylinder head and away from the exhaust port. The crank end of the piston is boxed in, in this instance by the inwardly projected frusto conical head 43, so 15 shaped to conform to the contour of a packing gland 44 which extends from the head of the casing 10 within the cylinder 31.

Each member 43 of the piston is tapped to receive the end of a tube 45 which extends 20 through the packing gland 44 and forms a housing for the piston rod 46. The piston rods 46 are of any suitable form and are pivotally secured to the pistons in the ordinary way, as indicated at 47.

25 The end of each piston rod is tapered as at 48 to take into a tapered aperture which extends through a block 49 and in which it is held by a nut 50. Each block 49 is provided with trunnions 51 which rock in bearings 30 formed in the prongs of the yoke end of a pin 52 and end blocks 53 which are bound on the yoke ends by machine screws or otherwise. The pins 52 are spaced at suitable intervals about the disk 21 of which they 35 extend radially, the plate being cored for their reception. The pins are bound in place by the clamping straps 53 one member of which is integral with a rib 23 and the other member clamped to the first member 40 by bolts or otherwise. A collar 54 may be provided on each pin to lock the same against longitudinal movement.

A hub 55 is secured by a key 56 or otherwise to the shaft 30 and the hub is formed 45 with a conical flange 57 provided with spaced apertures 58. An annular plate extends from the conical flange, with which it is integral, and extending from one face of this plate are vanes 59 which are arranged 50 radially. As is evident this structure provides a fan which rotates between the cylinders.

A head plate 60 has a central hub 61 which forms a bearing for the shaft 30 and 55 this plate is secured in place by machine screws 62 which are threaded into ears 63 which extend from the cylinder heads. The head plate is formed with an annular series of hoods 64 adapted to take over the cylinder heads and direct air across the heads and 60 pass through the apertures 58, from whence

it is directed by the fan against and between the sides of the cylinders.

Attaching lugs 65 are provided at suitable points on the device for the purpose of anchoring or connecting the motor to suitable supports.

Fuel is supplied to the motor in any usual and well known manner and explosion is had by a spark produced in any of the ordinary ways. The cylinders are exploded in rapid succession causing the edge of the plate 21 to be depressed with a gyratory movement, which imparts rotary motion to the shaft.

75 While the motor is here shown as placed on its side it is to be understood that the same may be placed in an upright position if desired. This would probably be of particular advantage when the motor is driving a helicopter.

Having thus described the invention, what is claimed, as new, and sought by Letters Patent, is:

1. In a motor, a support, a plate mounted for gyration in the support, cylinders mounted on the support, pistons in the cylinders, means for connecting the plate and cylinders, a shaft journaled in the support, a fan hub keyed to the shaft, said hub including a conical flange to provide a pocket, and having spaced apertures formed therein, vanes integral with the hub and adjacent the pocket, for drawing air through the apertures and pocket, said cylinders being arranged annularly about the fan.

2. In a motor, a support, cylinders on the support, pistons in the cylinders, a shaft journaled in the support, a fan hub keyed to the shaft, fan blades integral with the hub, said fan hub having means disposed between the fan blades for allowing air to be drawn therethrough by the fan blades, said cylinders being arranged annularly about the fan.

3. In a motor, a support, cylinders on the support, pistons in the cylinders, a shaft journaled in the support, a fan hub keyed on the shaft, said hub having a pocket formed adjacent one extremity thereof, the walls of the pocket having openings formed therein, fan blades integral with the hub, and adjacent the openings for drawing air through the openings, said pistons being arranged annularly about the cylinders.

115 In testimony that I claim the foregoing as my own I have hereto affixed my signature in the presence of two witnesses.

FRANK WOOD.
